(73) Assignee: **Meadwestvaco Corporation**, Glen Allen, VA (US)

(57) **CLAIM**

(**) Term: **14 Years**

The ornamental design for a container with retaining arm for holding media, as shown and described.

(21) Appl. No.: **29/217,492**

DESCRIPTION

(22) Filed: **Nov. 18, 2004**

FIG. 1 is a perspective view of a container with retaining arm for holding media disc, in open condition, showing our new design;

(30) **Foreign Application Priority Data**

FIG. 2 is a top plan view thereof;

May 18, 2004 (EM) 000178835

FIG. 3 is a bottom plan view thereof;

(51) **LOC (8) Cl.** **06-04**

FIG. 4 is an end elevation view thereof;

(52) **U.S. Cl.** **D6/635**

FIG. 5 is an end elevation view of the opposite end thereof;

(58) **Field of Classification Search** D6/407,

FIG. 6 is a side elevation view thereof, the opposite side being a mirror image;

D6/629–634; 206/209, 307, 307.1, 308.1,

FIG. 7 is a perspective view of the retaining arm member with the container removed for ease of illustration;

206/310; 281/4, 3.1, 15.1, 29; D9/415,

FIG. 8 is a top plan view thereof;

D9/420, 423, 432; D3/276, 289, 294, 295

FIG. 9 is a bottom plan view thereof;

See application file for complete search history.

FIG. 10 is an end elevation view thereof;

(56) **References Cited**

FIG. 11 is an end elevation view of the opposite end thereof;

U.S. PATENT DOCUMENTS

FIG. 12 is a left side elevation view thereof; and,
